US0D1109918S

(12) **United States Design Patent** (10) **Patent No.:** **US D1,109,918 S**
(45) **Date of Patent:** **** Jan. 20, 2026**

(54) **LIGHT CLIP**

(71) Applicant: **WUXI NEON ELECTRICAL EQUIPMENT Co., Ltd.**, Wuxi (CN)

(72) Inventor: **Shiwen Zhao**, Wuxi (CN)

(73) Assignee: **WUXI NEON ELECTRICAL EQUIPMENT Co., Ltd.**, Wuxi (CN)

(**) Term: **15 Years**

(21) Appl. No.: **29/971,975**

(22) Filed: **Nov. 7, 2024**

Related U.S. Application Data

(63) Continuation-in-part of application No. 29/952,983, filed on Jul. 18, 2024.

(57) **CLAIM**

The ornamental design for a light clip, as shown and described.

DESCRIPTION

FIG. 1 is a front perspective view of a light clip, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the light clip, which form no part of the claimed design.

1 Claim, 8 Drawing Sheets
